UNITED STATES PATENT OFFICE

HOWARD H. LANNING, OF TOPEKA, KANSAS

FIRE DOOR

Application filed July 3, 1929. Serial No. 375,810.

My invention is especially adapted to fire doors for locomotives and relates more particularly to the fire door in conjunction with means for conveying air, in regulable quantities, to the door, whereby the air may be admitted to the fire box with the door in closed position; the invention being especially intended for use in conjunction with an oil burning type of locomotive fire box.

10 The invention has for its object the provision of a construction whereby the air is admitted as previously stated, the admitted or inflowing air being deflected toward the fire without the necessity of opening the fire door and therefore without the dangers encountered with constructions as heretofore employed.

15 The invention also involves the construction of an air chambered door provided with a sand-introducing channel therein formed and arranged so as to not interfere with the admitted air which is introduced into the chambered fire door by air conveying means having a controllable air inlet which inlet is 20 disposed at a point removed from the firing position of the enginemen; said conveying means, in conjunction with the chambered door, being adapted, in the event of fire box or flue explosions to convey the force of such 25 explosions to a point removed from the operating positions of the crew.

30 The objects and advantages of my invention will be readily comprehended from the detailed description of accompanying drawings, wherein—

35 Figure 1 is an elevation of the rear end of an oil burning type of locomotive fire box, portions being broken away, illustrating the application of my invention thereto.

40 Figure 2 is a vertical sectional view taken substantially on the line 2—2 of Figure 1.

45 Figure 3 is a vertical sectional elevation taken substantially on the line 3—3 of Figure 2 looking in the direction of the arrows.

50 Figure 4 is a vertical sectional view of a lower end of the mechanism shown in Figure 2 illustrating the air admitting means in open position.

55 I have illustrated the application of my invention to an oil burning type of locomotive

fire box; the invention contemplating the provision of an air conduit means whereby air may be uniformly admitted at all points into the fire box through the fire door opening.

55

For purposes of exemplification, I have shown the invention applied to a fire box door flanging of the oval type of fire door opening; the flanging, which is indicated at 44, being known as the "O'Connor" fire door flange. It will be understood, however, that the fire door opening and therefore the fire door and ring may be modified to suit any form of fire box door flanging; whether the fire door opening be oval, square, round or any other suitable shape.

60

65 The back head of the fire box is shown at 45 provided with the fire door opening which is surrounded by a fire door frame 46 which is secured about the opening and held in place by a suitable number of studs 47. The frame 46 is of contour in keeping with the contour of the opening and is provided with the outwardly disposed flange portion 48 to provide a seat for the fire door 49 which is hingedly secured at one side to the fire door frame 46 by means of the laterally extending lugs 50 formed integral with the frame 46 and apertured to receive the hinge pin 51 which also extends through the apertured lugs 52, 52 formed integral with one side of the fire door 49. The opposite side of the fire door 49 is shown provided with a lug 53 which is apertured to receive stud 54, secured in the fire door frame 46, threaded to receive the nut 55 whereby the fire door is firmly held in closed position.

70

75 The fire door 49 is doubled walled and formed to provide an air receiving chamber 56 throughout. The rear wall of the fire door 49 is provided with an opening 57 disposed throughout the upper part of the fire door and partially about a sand introducing opening 58 which is formed by the downwardly sloping and transversely disposed conduit 59, see Figure 2, extending from the outer wall to the rear wall of the door and preferably integral therewith; with the opening 58 communicating with the fire door opening of the fire box.

80

85

90

95

100

The outer end of the sand introducing conduit 59 is provided with a closure member or cover 60 which is shown pivoted on a stud 61 secured to the outer wall of the door 5 so as to permit the cover member 60 to swing upwardly into uncovering position; the lower end of the closure member or cover being held in place by a keeper lug 62. The stud 61 is of length sufficient to also receive a 10 clamp member or lever 63 which is screwed thereon and by means of which the closure member or cover 60 may be clamped into either closed or open position. The keeper lug 62 and clamp member 63 securely hold 15 the cover 60 in place and prevent it being blown away in the event of an explosion. The closure member 60 normally is in closed position. The opening 58 permits the introduction of sand into the fire box during 20 operation for the purpose of cleaning the fire box flues; the sand being usually introduced in comparatively small quantities; the sand being caused to flow into the fire box by the draft of the locomotive which carries 25 the sand rapidly through the flues and cuts away the soot, corrosion, etc. encountered in oil burning locomotives.

The lower side or bottom of the fire door 49 is shown slightly flared laterally and the 30 bottom of the chamber therein left open to effect communication at 64 with the upper open end of the hollow member or air conveying conduit 65. The conduit in the construction shown, by reason of the type of fire 35 box door employed, is provided with a rear wall 66 in addition to the front and side walls.

The air conveying member or conduit 65 is shown firmly secured to lugs 67 on the fire 40 door frame 46 by means of bolts which pass through apertured lugs 68 formed on opposite sides of the conduit, as shown in Figures 1 and 3.

The lower end of the conduit 65 is provided with a closure member or damper 69. The damper 69, at one end, has an extension 70 terminating in an apertured bifurcation 71 to receive the lower end of operating lever 72 therebetween and which is pivotally secured thereto by a suitable pin 73.

The damper 69 is hingedly secured to the conduit 65 as indicated at 74, 74, to permit the damper to be swung downwardly into open position.

The position of the damper is controlled by reciprocatory or up-and-down movement of the lever 72, which is provided with a longitudinal slot 75 through which a stud 76 extends; the latter being secured at one end in a lug 77 which may be formed integral with the side of portion 65. The outer end of stud 76 is provided with a clamp member or lever 78 whereby the operating lever 72 is 65 firmly clamped in its adjusted positions and

consequently damper 69 also held in its closed and adjusted positions.

Before the fire door 49 is bolted into place in the normal closed position shown in Figure 2, a deflector 79 is put into place. This deflector is formed to extend or slope downwardly through the fire door opening in the back head as more clearly shown in Figure 2. The deflector is preferably of the arcuate formation shown and is provided at opposite 75 sides with lugs 80, 80, which fit into recesses 81 formed in the door frame 46. The top of the deflector 79 is also provided with a flange 82 which fits into the recessed portion of the flange 48 of the door frame or ring 80 46 and consequently is firmly held in place by the door 49 which in an oil burning type of locomotive normally remains closed.

The deflector 79 overhangs the opening 57 in the rear wall of the fire door and therefore directs the inflowing air downwardly toward the fire in the fire box. The deflector, during operation, becomes heated and by reason of its shape and position the inflowing air is caused to come into contact 90 with it and the air thereby heated as it passes into the fire box.

The inner end of the deflector or air directing member 79 is shown provided with a series of holes 83. These holes permit air 95 to pass therethrough, which not only aids combustion and prevents unequal temperatures in the fire box door flange 44; but also tends to protect the deflector from overheating.

In order to enable the engine crew or firemen to observe the condition of the fire, the cover 60 for the sand introducing opening 58 is provided with a peep hole 84; and the cover 60 is shown also provided with a lug 85 which enables easy operation of the sand hole cover about its pivot point 61, after the clamp member or lever 63 has been loosened.

The air conveying member or conduit 65 is made to extend down through the firing deck or cab floor 17 of the locomotive so that the damper and therefore the air inlet end are located beneath the deck.

With my improved structure, air in desired amounts may be admitted into the fire box by forcing lever 72 downwardly (after releasing clamp member 78) thereby forcing damper 69 into open position to an extent sufficient to admit the desired quantity of air necessary to effect the required combustion, without the necessity of opening the fire door or sand hole cover.

My improved device provides means whereby the amount of admitted air may be controlled or regulated, as the damper may be held in either its closed or adjusted positions by screwing the lever 78 into clamping relation with the operating lever 72; the slot 75 in the operating lever 72 being of length sufficient to permit the damper to be 130

swung into complete open position when desired.

In service, the damper 69 is open to an extent which will admit the required quantity of air. In the event of fire box or flue explosions, the force of such explosions will pass through the chamber 56 of the fire door, down through conduit 65 to a point beneath the firing deck 17 and allowed to discharge 10 through the opening controlled by the damper, thus protecting the engine-crew from injury. The usual fire door, as heretofore employed, does not afford relief and is frequently blown loose from its fastening, causing 15 serious injury and loss of life.

When it is necessary to enter the fire box, this may be accomplished by removing nut 55 from stud 54 which allows the fire door 49 to be swung on its hinge-pin 51. 20 I have shown my invention applied to a certain type of locomotive fire box at present in use, but it will be understood that the invention is applicable to other types with slight variations in contour to suit the form 25 of fire box door flanging; and while the exemplification is believed to be the best adaptation, which has been described in terms employed for description and not as terms of limitation, modifications may be made 30 without, however, departing from the spirit of my invention.

What I claim is:

1. A firebox having a fire door opening, a ring secured about said opening and provided with recesses in its upper outer face, a chambered fire door mounted on said ring, the chamber of the door having openings at the bottom and at the rear of the door, the door having a sand introducing channel disposed transversely therethrough and communicating with the fire door opening, a closure for said channel, an air deflecting member disposed about the upper side of the opening in the rear wall of the door and extending into the fire door opening, said deflecting member being flanged at its outer end and said flanges seating in the ring recesses and held in place by the rear wall of the fire door, a hollow open ended member secured 40 to the ring with one end communicating with the opening in the bottom of the door while the other end is disposed beneath the firebox deck and constitutes the air inlet, adjustable means for controlling said air inlet, and 45 means whereby said adjustable means may be controlled and locked in adjusted positions.

2. A fire box provided with a fire door opening, a ring secured to the fire box about 50 said opening, a hollow fire door secured to said ring and provided with a chamber extending throughout the door and open at the bottom of the door below the fire door opening in the fire box, a sand introducing 55 conduit integral with the front and rear

walls of the door and open at its ends, the door having an opening in its rear wall disposed across the top and sides of said conduit for establishing communication between the chamber of the door and the fire box 70 opening, an open ended hollow air conveying member secured at its upper end to said ring with the upper end fitting the open bottom of the fire door while the other end is disposed beneath the firing deck of the fire box, 75 and regulable closure means hingedly secured to the lower end of said member for regulating the air admitted into said member and the fire door.

3. A firebox provided with a fire door 80 opening, a ring secured about said opening, a hollow fire door mounted on said ring and provided with a sand introducing conduit whose ends are integral with the front and rear walls of the fire door, the rear wall of the door having an opening disposed across the top of said conduit and communicating with said door opening, the bottom of the door being open, an open-ended air conveying chamber of substantially the same width 85 as the open bottom of the door secured to the ring with its upper end abutting the open bottom of the door, while the opposite end of the member is disposed beneath the firing deck of the firebox and constitutes the air inlet, a damper hingedly secured to said member for controlling said inlet, and a lever pivotally secured at its lower end to the damper and reciprocatingly secured to said member for regulating said damper and 90 for holding the same in adjusted positions. 95

4. A firebox having a fire door opening, a ring secured about said opening, a chambered fire door mounted on the ring, the chamber of the door being open at the bottom of the door and having an opening in the rear wall communicating with the fire door opening in the fire box, open ended air conveying means disposed throughout the width of the fire door and secured about the opening in the bottom of the door, said means being arranged vertically and extending downwardly beneath the firing deck of the firebox, regulable closure means secured to the bottom of the air conveying means for 100 controlling the air admitted through the bottom open end thereof, and a lever reciprocatingly mounted on said air conveying means whereby the closure means is controlled. 105
